UNITED STATES PATENT OFFICE.

WOLCOTT A. HULL, OF NEW YORK, N. Y.

ORNAMENT FOR LAMP-SHADES.

SPECIFICATION forming part of Letters Patent No. 350,058, dated September 28, 1886.

Application filed June 7, 1886. Serial No. 205,416. (No model.)

To all whom it may concern:

Be it known that I, WOLCOTT A. HULL, of New York, in the county and State of New York, have invented a certain new and useful Improvement in Ornaments for Lamp-Shades, 5 of which the following is a specification.

My improvement consists in the combination of a shade and separate ornaments therefor, severally comprising a portion forming a 10 segment of a shade-crown, a portion extending downwardly below the same, and projections whereby it may be secured to a shade.

In the accompanying drawings, Figure 1 is a side elevation, partly in section, of a lamp-shade having ornaments embodying my improvement. Fig. 2 is a plan or top view of the same.

Similar letters of reference designate corresponding parts in both figures.

20 A designates a shade, which may be of any desired shape and material. As shown, it has a circumferential flange, *a*, at its upper edge.

B designates ornaments, which may be made of metal or other suitable material and of 25 any desired configuration. They each have a portion, *b*, extended so as to form a segment of a circle, in such manner that when a sufficient number of them are placed together about a lamp-shade the portions *b* will meet or overlap at their ends, so as to form a continuous shade-crown. This construction of the orna-

ments is advantageous, because the extended segmental portions *b* have a bearing on the shade which tends to prevent the ornaments, when placed upon the shade, from canting to 35 one side or riding up. The ornaments are therefore steadied and caused to maintain a true position on the shade.

The ornaments are maintained upon the shade by means of hooks or tongues *c*, arranged upon the inside of the portions *b*, and bent in such manner that they may extend over the flange *a* on the shade. It will be observed that the hooks *c* are below the upper edge of the portions *b*, forming the segments 45 of the crown, and are consequently hidden from view. The hooks *c* may be either stamped up out of the ornaments or may be separately secured thereto by solder or otherwise.

What I claim as my invention, and desire to 50 secure by Letters Patent, is—

The combination of a shade and separate ornaments therefor, severally comprising a portion forming a segment of a shade-crown, a portion extending downwardly below the same, 55 and projections whereby it may be secured to a shade, substantially as specified.

WOLCOTT A. HULL.
